[57] CLAIM

The ornamental design for a toothpaste tube squeezer,
as shown and described.

DESCRIPTION

FIG. 1 is a front, top and side perspective view of the
toothpaste tube squeezer showing my new design;
FIG. 2 is a front elevational view thereof, the rear being
a mirror image of the front shown in FIG. 2;
FIG. 3 is a side elevational view thereof;
FIG. 4 is a side elevational view thereof;
FIG. 5 is a top plan view thereof; and,
FIG. 6 is a bottom plan view thereof.

FIG.1.

FIG. 2.

FIG. 5.

FIG. 6.

FIG. 3.

FIG. 4.
